ECHO REDUCING CIRCUIT FOR TELEVISION RECEIVERS

James Ernest Smith, Jackson Heights, N. Y., assignor to Radio Corporation of America, a corporation of Delaware

Application March 30, 1945, Serial No. 585,688

1 Claim. (Cl. 250—20)

1

The present invention relates to television systems, and more particularly to means for effectively eliminating in the reproduced image distortion caused by multipath reception.

In certain localities, especially urban areas, a received television image is often distorted by "ghost" patterns or echoes produced by reflections from buildings or other large objects having dielectric constants which differ radically from that of free space. If the path of the reflected signal is not appreciably greater than that of the direct signal, the only effect observed will be a slight blurring of the outlines of the reproduced image. This might be regarded as much the same general appearance in the final image as an absence of the higher signal frequency components. However, if there is an appreciable difference in the lengths of the two paths, separate images often appear on the screen of the reproducing device. Such images are usually termed "ghosts." They may be at times either negatives or positives.

In certain instances, the objectionable effects of multipath reception may be eliminated by the use of directional antennas. Such an expedient has proven only partially successful, however, since the reflected signal often arrives at the receiving antenna from approximately the same direction as the desired signal. Moreover, the orientation of such a directional antenna limits its reception to transmission from a single station. If programs are desired from any of several stations within the range of the receiver, a compromise adjustment must be found or else a rotatable antenna must be employed.

It has been found possible to employ two non-directive antennas to reduce the secondary path signal if these two antennas are connected to their respective receivers over a pair of transmission lines the lengths of which are so determined that the received signal arrives at one receiver later than at the other by an interval equal to the time-delay of the secondary path signal which is to be eliminated. If the time-delay of the reflected signal is two microseconds, for example, then one transmission line is selected to be longer than the other by such an electrical length as to produce two microseconds time-delay. Some of the disadvantages of such a system are the necessity for using two separate receivers, and the fact that the relative lengths of the two transmission lines are predetermined for the time-delay of a particular secondary path signal, or, in other words, for reception of transmissions from a single station.

Another system which has been proposed for

reducing the effects of multipath reception makes use of a portion of the main signal pulse which, after being time-delayed, is reintroduced into the receiver circuit in a manner to balance out the secondary path pulse. This method includes a time-delay cable the length of which is chosen equal to half the delay interval required multiplied by the velocity of electrical waves upon the cable. If the cable has an electrical velocity half the velocity of light, or 150,000,000 meters per second, which is a reasonable value, then a time-delay of two microseconds requires a cable 150 meters long. Not only is a cable 150 meters long cumbersome and difficult to enclose within a modern receiver, but, in addition, the fixed length of the cable limits its time-delay to a particular value, and does not permit delay variations which are required to effect cancellation of reflections selectively received from a plurality of transmitting stations and arriving over paths of various lengths.

According to one feature of the present invention, means are provided for effectively eliminating the effects of multipath reception, these means being of relatively small size compared to the dimensions of the time-delay cable above mentioned, and being so designed as to form an integral part of the receiver itself. Furthermore, by making such means easily adjustable by an observer, distortion resulting from signal reflections may effectively be cancelled out for each new station received during the time that the image from that particular station appears on the screen of the reproducing device.

35 One object of the present invention, therefore, is to provide means for effectively eliminating the effects of multipath reception in television systems.

40 A further object of the invention is to provide, in a television system, means whereby the observer of a reproduced image may eliminate the effects of multipath signal reception during observance of the image.

45 A still further object of the invention is to provide a multi-section delay and attenuation network associated with the video signal circuit of a television receiver, such network being readily adjustable by an observer during observance of the reproduced image to effectively include in the network one or more sections, and thus produce a wave so delayed and attenuated with respect to a desired signal wave as to effectively cancel any reflections which may be included in the video signal then being received by reason of 50 multipath reception.

Other objects and advantages will be apparent from the following description of a preferred form of the invention and from the drawings, in which:

Fig. 1 is a circuit diagram of a television receiver incorporating a preferred embodiment of the present invention;

Fig. 2 is a set of curves illustrating the operation of the circuit of Fig. 1; and

Fig. 3 is an alternative form of the delay and attenuation network of Fig. 1.

Referring first to Fig. 1, there is illustrated a television receiver of the superheterodyne type. The television signal received by antenna 10 is fed through an R. F. amplifier 12 to a converter 14, the latter also being supplied with energy from a local oscillator 16.

The video portion of the composite television signal output of converter 14 passes through a video I. F. amplifier 18, a video detector 20, and a video amplifier 22. The output of video amplifier 22 is applied to an image-reproducing device, such as a cathode-ray tube 24. The audio portion of the composite television signal output of converter 14 passes through a sound I. F. amplifier 26 and a sound detector and amplifier 28 to a sound-reproducing device, such as a loud-speaker 30.

In accordance with the preferred embodiment of the invention shown in Fig. 1, any echo or "ghost" signal which may be received by antenna 10 along with the desired video signal is reduced in intensity to a point where it can no longer cause objectionable distortion of the reproduced image. The means for accomplishing this object comprises a delay and attenuation network indicated in the drawing by the reference character 32. This network 32 is connected in parallel with the video signal circuit of the receiver by means of conductors 34 at some suitable point such as the input of the video amplifier 22.

Network 32 embodies the principle of a distortionless transmission line with the far-end impedance mismatched to provide a reflected signal wave having proper amplitude and time-delay characteristics to substantially cancel the received "ghost" image. To illustrate its operation, let a usual case be assumed wherein the incoming signal contains one pronounced echo of, say, one-quarter the intensity of the desired signal. If, at any instant, the desired signal consists of a short pulse, such as might be obtained from the camera tube during the scansion of an isolated dark body, then the incoming signal will appear as in curve (a) of Fig. 2, where 36 is the desired signal of amplitude h and 38 is its image having an amplitude of $h/4$.

The energy output of video detector 20 is divided between the video amplifier 22 and the delay and attenuation network 32, the latter, as above stated, acting as a distortionless transmission line. The portion of the energy output of video detector 20 entering the line travels along the line with a velocity determined by the constants thereof. If the far end of the line is short-circuited, this energy wave is reflected back along the line without change of amplitude (assuming the line is lossless). If the time-spacing between the desired signal pulse 36 and its image 38 is T seconds (Fig. 2), then the line length is adjusted in a manner hereinafter to be described to give T seconds time delay for the loop transmission of the signal, or, in other words, the time required for the signal pulse to travel down the line plus the time required for the re-

flected signal pulse to reach the input terminals of video amplifier 22 should be T seconds.

It has been assumed above that the echo pulse has an intensity equal to one-quarter of the desired signal pulse. If now the amplitude of the reflected wave is reduced to one-quarter of its original value by means hereinafter to be described, this reflected signal pulse together with its reflected image will appear as shown in 36' 10 and 38' respectively in curve (b) of Fig. 2, the 15 polarity of the reflected wave being reversed with respect to the received signal of curve (a) by the selection of a terminating resistance which is lower than the surge impedance of the line.

The actual signal appearing at the input terminals of video amplifier 22 is, therefore, equal to the sum of two components, one being that portion of the divided output of video detector 20 which is applied directly to the video amplifier 22, and which may be represented by curve (a), 20 and the other component being the remaining portion of the divided output of video detector 20 which is returned over conductors 34 after 25 being delayed and attenuated in the manner represented by curve (b).

The sum of curves (a) and (b) is shown in curve (c). It will be seen that the received "ghost" image 38 of curve (a) has been completely cancelled by the reflected signal pulse 36' 30 of curve (b), the latter pulse having the same amplitude $h/4$ as the "ghost" image 38 and being opposite thereto in phase.

It will also be noted that a new "ghost" image 38' is introduced into the signal input to the 35 video amplifier 22 as a result of the above mode of operation. However, the amplitude $h/16$ of this new "ghost" image 38' is only one-quarter of the amplitude $h/4$ of the original "ghost" image 38 or one-sixteenth of the amplitude h of the received signal pulse 36.

Obviously, by employing an additional transmission line of twice the electrical length of that described above and in parallel therewith, the same process may be repeated to cancel the 45 "ghost" image 38' and introduce a new image having an amplitude equal to $h/64$. However, such a procedure is unnecessary in most practical cases, since the signal-to-image intensity ratio of the circuit of Fig. 1 is 24 db., or considerably better than the signal-to-noise ratio of present day television receivers. In this connection, it has been found that a signal-to-noise ratio of 20 db. is satisfactory.

The delay and attenuation network 32 of Fig. 55 1 includes a series of low-pass filter sections 40, 42, 44 and 46 respectively connected to the contacts of a switch 48 which is so arranged that any desired number of these filter sections may be selectively included in the network 32. The 60 filter circuits shown in Figs. 1 and 3 are preferred over other arrangements in that they have good linear phase characteristics—that is, constant time delay over the filter passband. However, any other suitable type of low-pass filter system may if desired be used to simulate the transmission line.

The approximate time delay for each of the 65 filter sections 40, 42, 44 and 46 is given by the formula

$$T_d = \frac{.316}{f} \text{ seconds}$$

where f is the cut-off frequency of the filter. Thus for the present television signal fidelity of approximately 4 megacycles, a delay of about

.08 microsecond is obtainable per section in one direction, or a delay of about .16 microsecond per section for a loop transmission from the output of video detector 20 through the network 32 and back to the input terminals of video amplifier 22. Switch 48 allows variations in delay in steps of approximately .16 microsecond.

Since one scanning line or approximately 10 linear inches of image, on the average, are transmitted in approximately $\frac{1}{15000}$ second, it follows that $\frac{1}{16}$ inch displacement in the reproduced image requires a delay of about $\frac{1}{1500000}$ second or approximately .66 microsecond. Since four filter sections each having a delay of about .16 microsecond have a total delay of .64 microsecond, it will be appreciated that four filter sections can effectively cancel an echo that is displaced $\frac{1}{16}$ inch in the reproduced image. Similarly, eight filter sections can effectively cancel a "ghost" displaced $\frac{1}{8}$ inch. Inasmuch as the width of a single image element is roughly .008 inch, the above displacements are on the order of several such widths, and their correction by means of the present invention results in a considerable improvement in the detail of the reproduced image.

The above discussion has been concerned only with the time-delay feature of the network 32. This network in addition includes means for adjusting the amplitude of the reflected signal, such adjustment being provided by the variable terminating resistor 50 connected in series with switch 48. If the maximum value of this terminating resistor 50 is chosen equal to the surge or characteristic impedance of the line, then the reflected wave will always be inverted in phase with respect to the received signal, as shown in Fig. 2. The degree of mismatch—that is, the difference between the line surge impedance and the selected value of terminating resistor 50, determines the amplitude of the reflected wave, this amplitude being chosen to effect cancellation of the received "ghost" image in the manner above described.

It will be understood that the adjustments of switch 48 and resistor 50 are carried out manually while an image (preferably a test pattern) is viewed on the screen of the reproducing device.

Fig. 3 shows an alternative network 32' corresponding to the network 32 of Fig. 1. The addi-

tion of two variable resistors 52 and 54 permits a more precise adjustment of the attenuating characteristics of the network. Furthermore, while only four filter sections 40, 42, 44, and 46 have been shown in Fig. 1, any desired number of these filter sections may be connected in series as indicated by the broken line 56 in Fig. 3, the number of contacts on switch 48 being determined accordingly.

From the foregoing description it will be understood that various omissions, substitutions, and changes in the form and details of the apparatus described may be made by those skilled in the art without departing from the spirit of the invention.

Having now described the invention, I claim:

In a television system in which distortion in the reproduced image results from the multipath reception of the transmitted signal, the combination of means for receiving both the desired signal and the reflected signal, a multi-section delay and attenuation network, manually-adjustable means for applying a portion of the received signal selectively to at least one section of said delay and attenuation network, and means for combining the output of said delay and attenuation network with the remaining portion of said received signal, said delay and attenuation network including an adjustable terminating resistor having a maximum value approximately equal to the surge impedance of the network.

JAMES ERNEST SMITH.
